US00D396573S

United States Patent [19]

Dewitt

[11] Patent Number: Des. 396,573

[45] Date of Patent: **Aug. 4, 1998

[54] CHECK STAND COUNTER

3,960,420 6/1976 Speraw et al. 312/140.1
4,138,000 2/1979 Hartup 186/61

[75] Inventor: Wayne Dewitt, Jacksonville, Fla.

Primary Examiner—James Gandy

[73] Assignee: Load King Manufacturing Co., Inc.,
Jacksonville, Fla.

Assistant Examiner—Linda Brooks

Attorney, Agent, or Firm—Thomas C. Saitta

[**] Term: 14 Years

[57] CLAIM

[21] Appl. No.: 62,269

The ornamental design for a check stand counter, as shown
and described.

[22] Filed: Nov. 12, 1996

DESCRIPTION

[51] LOC (6) Cl. 06-99

FIG. 1 is a top plan view of a check stand counter showing
my new design;

[52] U.S. Cl. D6/402

FIG. 2 is a front elevational view thereof;

[58] Field of Search D6/396, 397, 402;
312/140.1; 186/59-68

FIG. 3 is a left side elevational view;

FIG. 4 is a rear elevation thereof;

FIG. 5 is a bottom plan view thereof; and,

FIG. 6 is a right side elevational view.

The broken lines shown throughout the views illustrate
environmental structure and form no part of the claimed
design.
